UNITED STATES PATENT OFFICE.

CHARLES A. STEWART, OF ROLLINSFORD, NEW HAMPSHIRE.

CLOTH-FOLDING MACHINE.

1,109,801.

Specification of Letters Patent. Patented Sept. 8, 1914.

Application filed January 16, 1913. Serial No. 742,109.

To all whom it may concern:

Be it known that I, CHARLES A. STEWART, of Rollinsford, in the county of Strafford and State of New Hampshire, a citizen of the United States, have invented a new and useful Improvement in Cloth-Folding Machines, of which the following is a full, clear, and exact description, reference being had to the accompanying drawings, forming a part of this specification, in explaining its nature.

The present invention relates to an improvement in cloth folding machines and especially to that type of cloth folding machine described in my copending application for Letters Patent of the United States, filed July 13, 1912, Serial No. 709,138, which makes that kind of fold in which the cloth is folded reversely back upon itself.

The present invention has for its object the application of power to the machine for operating it and also for carrying the operator so that it will not only be very easy for one operator to control the machine but also to render such manual assistance as may be necessary in the folding of the cloth.

The invention can best be seen and understood by reference to the drawings in which—

Figure 1 shows in side elevation a folding machine like that described in my said application and having applied thereto an attachment like that comprising my present invention. Fig. 2 is a section on the line 2—2 of Fig. 1.

Referring to the drawings—1 represents the table forming the bed of the machine. 2 is the carrier. The carrier is mounted to run lengthwise over the table by straps 3 connecting with the body of the carrier at either side thereof and carrying at their lower ends flanged wheels 4 which run on tracks 5 secured to the legs or standards 6 supporting the table. The carrier 2 is provided with a head bar 7 from which project downwardly and forwardly extending arms 8 provided with turned ends in which lies a rod 9.

In Fig. 1 the carrier is shown occupying a retracted position. Upon the table forward of the carrier when in its retracted position are arranged sets of posts 10, 11, 12, 13, respectively, by and between which the cloth is folded in the operation of the machine as the carrier is moved back and forth over the table.

Inasmuch as the present improvement pertains only to an attachment or mechanism for moving the carrier alternately back and forth over the table and for carrying the operator at the same time so that he may always be in a position to most effectually assist in the operation of the machine, it is accordingly unnecessary to describe in further detail the actual operation of folding the cloth which has now become well understood in the art.

Referring now to the attachment comprising my present invention: Secured to the body of the carrier and depending therefrom to lie alongside and parallel with the front side of the machine is a frame 14 carrying a platform 15 upon which the operator may stand. Secured to this platform are casters 16 assisting in the support thereof and which may run upon the floor alongside the machine or upon any other suitable runway or support.

Arranged at the rear of the machine back of the carrier and frame 14, when the carrier is in its retracted position, is a shaft 17 bearing a wheel or pulley 18 to which power may be applied for turning the shaft. This shaft extends through one of the legs or uprights 6 at the rear of the machine, a box 35 or bearing 19 being provided (see Fig. 2) in which the shaft may turn. The other end of the shaft may be supported in any suitable manner by a bearing, not shown. Fixed to the shaft 17 is a grooved pulley 20. Around this pulley is passed an endless belt 21 having oppositely-moving portions 22 and 23, respectively. The end of the belt opposite the pulley 20 is passed around a pulley 24 carried by a hanger 25 which depends from the table 1 of the machine at a point beyond the set of posts 12, 13. The disposition and arrangement of the pulleys 20 and 24 are also such that the belt 21 will extend along the front side of the machine just back of the frame 14 borne by the carrier so that the operator standing upon the platform 15 will be supported in a position where he cannot contact with the belt by reason of the intervention of the frame 14.

It is the oppositely-moving portions 22 and 23 of the belt which operate to move the carrier and platform 15 supporting the operator alternately forward and backward within the limitations of a proper operation of the carrier and this is accomplished

in the following manner:—Secured to the platform 15 are levers 26 and 27. These levers are pivoted respectively to brackets 28 fixed to the platform 15. The lever 26 carries on the end thereof a footrest or pedal 29; the lever 27, a footrest or pedal 30. Both the levers 26 and 27 extend backwardly through openings formed in the frame 14. Each of these levers has pivoted to it a link 31. One of these links connecting with the lever 26, extends upwardly to a point above the portion 22 of the belt, and the other link connecting with the lever 27, extends upwardly to a point above the portion 23 of the belt. Pivotally connecting with the upper ends of these links are other pivoted links 32 which extend substantially at right angles to the links 31, and one of which links lies just above and adjacent the running portion 22 of the belt and the other just above and adjacent the running portion 23 of the belt. Both the links 32 are pivotally secured to turn upon studs 33 fixed to the frame 14. Carried by the links 32, respectively, and secured to the outer ends of these links are clutch members 34 and 35, respectively. Of these clutch members the clutch member 34 is carried by that set of links connecting with the lever 26 and the clutch member 35 carried by that set of links connecting with the lever 27. These clutch members lie also just above the respective running portions of the belt and in alignment therewith, whereby said members may be moved to engage the belt as the links bearing the same are moved in one direction, or the clutch members occupy a disengaging position with respect to the belt as the links bearing the same are moved in a reverse direction.

Adjacent the under sides of the respective running portions of the belt opposite the clutch members 34 and 35 and with which these clutch members are adapted to operate, are other clutch members 36 and 37, respectively. These clutch members are secured to the frame 14 of the machine by studs 38. Both the clutch members 36 and 37 preferably consist as shown of small shallow grooved wheels mounted to turn upon their supporting studs 38 and in the grooves of which wheels the opposite running portions of the belt are contained.

The operation of the device is as follows:—Assuming the carrier to be in a retracted position with the operator standing upon the platform or running-board 15, he will first operate the lever 26 by depressing the pedal 29. Thereupon the clutch member 34 will be made to engage the clutch member 36 and running portion 22 of the belt, when the carrier, the frame 14 and platform 15 will be moved by the belt as long as the pedal 29 is held depressed and the clutch engagement between the members 34, 36 and the belt maintained, or, in other words, until the carrier has been moved forward over the table a proper distance for folding the cloth which depends upon the length of the fold to be obtained. As the carrier approaches the limit of its movement the foot of the operator is removed from the pedal 29 releasing the clutch when the weight and normal gravitated position of the parts is sufficient to return the clutch member 34 to a disengaging position. The retraction of the carrier and platform carrying the operator is obtained simply by throwing the clutch member 35 into engagement with the clutch member 37 and the running portion 23 of the belt. This effect is obtained simply by depressing the lever 30 when the parts will be carried back by the running portion 23 of the belt to a proper retracted position. As the parts approach their proper retracted position the clutch may be released from the belt by the release of the foot of the operator from the pedal 30.

It is desirable that some means be employed for automatically releasing the clutch-forming mechanism from the running portion 22 of the belt upon the termination of the forward movement of the carrier over the table, or as the carrier approaches the limit of its forward movement. Such automatic release I have provided in the member 40 secured to one of the tracks 5 at the forward end of the table, or at such point as may be found desirable to automatically release the clutch-forming mechanism connecting with the running portion 22 of the belt. The disposition and adaptation of this member are such that when the portion 22 of the belt has borne the carrier and stand to about the limit of their forward movement, then the clutch-forming mechanism connecting with this portion of the belt will have reached a point where the links 31 and 32 thereof or the joint connecting these links will engage the member 40 and become depressed thereby, which accordingly operates to automatically release the clutch member 34 from the belt.

A similar mechanism may be provided for automatically releasing the clutch-forming mechanism connecting with the portion 23 of the belt upon the termination of the reverse movement of the carrier and operator's stand. This is unnecessary, however, in practice owing to the fact that it is unnecessary for the carrier to assume any specific retracted position back of the first set of links, it being necessary only that the carrier be moved well back of these links which gives ample time for the operator to release the clutch connecting with the running portion 23 of the belt.

By the means above described the entire machine may be controlled by one operator.

standing upon the platform 15. No walking upon the part of the operator is necessary for he is borne with the carrier carrying the cloth to just those points where he 5 can best watch the fold and render such manual assistance as may be necessary.

Having thus fully described my invention, I claim and desire to secure by Letters Patent of the United States:—

1. In a folding machine, the combination with a raised table, of a carrier movable over said table with a forward and reverse movement, an operator's stand secured to said carrier and movable therewith, the 15 same comprising a frame connecting with said carrier and depending therefrom alongside said table and a platform carried by said frame, mechanism whereby power may be applied for moving said carrier and operator's stand with a forward and reverse movement, and means carried by said stand whereby an operator standing on said platform may control the application of power to said carrier and stand for moving the 25 same as aforesaid.
2. In a folding machine, the combination with a table, of a carrier movable over said table with a forward and reverse movement, an operator's stand secured to and movable 30 with said carrier, pulleys oppositely arranged, a belt passed around said pulleys with portions thereof movable in opposite directions upon the application of power to said pulleys, and separate releasable clutch-forming mechanisms carried by said stand and attachable respectively to the opposite running portions of said belt.
3. In a folding machine, the combination with a table, of a carrier movable over said 40 table with a forward and reverse movement,

an operator's stand secured to and movable with said carrier, pulleys oppositely arranged, a belt passed around said pulleys with portions thereof movable in opposite directions upon the application of power to 45 said pulleys, foot-levers mounted upon said stand, and separate releasable clutch-forming members controlled respectively by said levers and attachable respectively to the opposite running portions of said belt. 50

4. In a folding machine, the combination with a raised table, of a carrier movable over said table with a forward and reverse movement, an operator's stand secured to said carrier and movable therewith, the 55 same comprising a frame connecting with said carrier and depending therefrom alongside said table and a platform carried by said frame, mechanism whereby power may be applied for moving said carrier and operator's stand with a forward and reverse movement, the same comprising in part a power-driven endless belt with portions thereof running in reverse directions, fixed clutch members secured to said frame adjacent the respective running portions of said belt, movable clutch members cooperating therewith to grip said opposite-running portions of the belt, levers pivotally secured to said platform and link-forming connections 60 interposed between said levers and said movable clutch forming members whereby said members may be controlled by said levers with relation to said fixed clutch members and said belt. 65
